PUFFED TEXTILE FABRIC

Gerald D. Martin, Maulden, Mo., assignor to United States Rubber Company, New York, N. Y., a corporation of New Jersey

Application October 9, 1957, Serial No. 48,031

Term of patent 14 years

(Cl. D92—1)

Fig. 1

Fig. 2

Fig. 1 is a plan view of a puffed textile fabric showing my new design, and

Fig. 2 is a sectional view of the fabric of Fig. 1 along the line 2—2.

The design is a surface of raised puffs arranged on a puffed textile fabric as shown in Fig. 1. The bottom, horizontal line in Fig. 2 represents one of the interlaced threads which hold the puffs raised.

I claim:

The ornamental design for a puffed textile fabric, as shown and described.
